George Lander Jacques

UNITED STATES PATENT OFFICE.

GEORGE LANDER JACQUES, OF NEILLSVILLE, WISCONSIN.

SKEE-SKATE.

1,222,767.

Specification of Letters Patent. Patented Apr. 17, 1917.

Application filed February 19, 1915, Serial No. 9,337. Renewed March 7, 1917. Serial No. 153,168.

To all whom it may concern:

Be it known that I, GEORGE LANDER JACQUES, a citizen of the United States, residing at Neillsville, in the county of Clark and State of Wisconsin, have invented a new and useful Skee-Skate, of which the following is a specification.

My invention relates to improvements in skee-skates in which each skee-skate is constructed with two parallel runners with means for fastening the same to the foot which will allow the free action of the foot upon a pivot near the toe thereof and one or more tilting dogs operating between said runners; and the objects of my improvements are, first, to provide a means which will prevent said skee-skate at all times from slipping backward without hindering or impeding its forward motion; second, to provide for an arrangement and construction of said dogs so that their action will be free and unobstructed by accumulations of ice or snow; third, to provide a proper cushion to deaden the noise of the action of said dogs.

I attain these objects by the mechanism illustrated in the accompanying drawings, in which—

Figure 1 is a detailed view in perspective of the entire skee-skate as it appears when the operator is sliding forward upon it; Fig. 2 is a detailed view in perspective of the entire skee-skate as it appears when the operator is pushing backward upon it in order to propel himself forward on the other skee-skate; Fig. 3 is a detailed view in perspective of a section of said skee-skate with a part of one runner removed so as not to obstruct the view showing in detail the construction and arrangement of one of said dogs as it appears when the operator is pushing backward on the skee-skate to which it is attached; Fig. 4 is a detailed view in perspective of a section of one of said skee-skates with a portion of one runner removed so as not to obstruct the view showing in detail the construction and arrangement of one of said dogs as it appears when the operator is sliding forward on the skee-skate to which it is attached; Fig. 5 is a detailed view in perspective of the cushion used to deaden the noise of the action of said dogs; Fig. 6 is a detailed view in perspective of the foot plate used in attaching said skee-skate to the foot as the same appears when detached from said skee-skate and all

straps removed therefrom; Fig. 7 is a detailed view in perspective of the bracket used in attaching the foot plate shown in Fig. 6 to said skee-skate.

Similar letters refer to similar parts throughout the several views.

The runners *a*, the braces *b* and the platform *j* constitute the framework of the skee-skate. The shafts *o* pass through the runners *a* and form a pivot upon which the dogs *c* tilt or turn. The shafts *l* pass through the runners *a* and the cushion *k* and are so located that when the operator pushes backward on the skee-skate the upper part of the dog *c* will rest on said cushion *k* supported by said shaft *l* and hold said dog *c* in such position that the portion of said dog *c* marked *c*¹ will be held rigid substantially at right angles to the runners *a* and projecting into the snow or ice upon which the runners *a* rest and also so located that as the skee-skate moves forward and the dog *c* tilts backward the portion of said dog *c*¹ will be allowed to rise only high enough to clear the ice and snow of the track over which the skee-skate is traveling and hold said dog *c* in such a position that the specific gravity of the portion *c*¹ of said dog *c* will cause it instantly to drop into and penetrate the ice and snow of the track when the operator pushes backward on said skee-skate. Said skee-skate may be constructed with only one dog *c* located either in front of or behind the foot of the operator or with one or more dogs *c* either in front of or behind the foot of the operator or with one dog *c* in front of and one behind the foot of the operator but I prefer to carry out this feature of my invention in the manner shown in Fig. 1 with two dogs *c* used in front of and two behind the foot of the operator.

The braces *b* are attached to the runners *a* by rivets at *n* and hold said runners together one being located near each end of said runners and the platform *j* is attached to said runners by screws or bolts at *m* and braces and holds the runners *a* together and also affords a platform upon which the foot of the operator rests when he is sliding forward on that skee-skate. The cushion *k* is a tube composed of rubber, cloth or any other soft substance that will deaden the noise of the dogs *c*—*c*¹ in striking against the shaft *l* which said shaft *l* passes through and is inclosed within said cushion *k*.

A shaft passes through the runners *a* and the bracket *i* at *s* and forms a pivot upon which the bracket *i* turns the said bracket *i* carrying the foot plate *d* attached to it 5 by rivets at *q* and the said foot plate *d* carrying the toe strap *f*, the heel strap *g* and the instep strap *h* attached thereto at *r* by rivets and made adjustable to the operator's foot by buckles at *p*. At the forward end 10 of the foot plate *d* on either corner thereof is a diagonal raised lip or collar *e* to hold the operator's foot in place preventing it from slipping forward and the heel of the operator's foot occupies the open space immediately at the rear of the foot plate *d* and the operator's foot *s* held from slipping backward by the heel strap *g* and is held firmly in place by the toe strap *f* and the instep strap *h* said straps *h* and *f* holding 15 the foot plate *d* firmly against the bottom of the operator's foot said foot plate *d* being constructed of spring steel or other substance that will produce a similar effect so that said foot plate *d* will bend with the 20 sole of the operator's foot but be rigid to any side motion and keep the operator's foot always in line with the runners *a*, the platform *d* being attached near its forward end to the bracket *i* by rivets at *q* and with 25 said bracket *i* turning upon the pivot formed by the shaft at *s* and permitting the heel of the operator's foot to be lifted high in the air without raising the rear end of the runners *a* from the track when the operator 30 pushes backward.

In operating said skee-skates one of said skee-skates is attached to either foot of the operator and in pushing backward alternately with either foot any backward motion 35 of the skee-skate is arrested by the projection of the dogs *c*¹ into the ice or snow of the track and the operator is enabled to propel himself forward sliding upon the skee-skate attached to the other foot and 40 thus proceeds in long sliding strides alternately sliding forward on either skee-skate as that skee-skate assumes a rearward position preparatory to pushing off upon it.

I am aware that prior to my invention

skees have been made with a tilting foot 50 plate pivoted to the runner thereof. I therefore do not claim such a combination broadly.

I am aware that in my application for a patent filed January 27th, 1915 I claimed 55 the combination in a skee or skate of two parallel runners. I therefore do not here claim such a combination broadly.

I claim:

1. The combination in a skee or skate of 60 two parallel runners carrying one or more tilting dogs between them provided with stops arranged to allow said dogs to tilt backward when the skee or skate moves forward and hold said dogs rigid substantially 65 perpendicular to the runners tending to stop any backward motion of the skee or skate when the operator pushes backward thereon said runners also carrying means to secure the same to the foot. 70

2. The combination in a skee or skate of 75 two parallel runners carrying one or more tilting dogs between them arranged to extend below said runners and assume a rigid position substantially perpendicular to the runners when the runners are moved backward and to tilt back and upward above the bottom of the runners when the runners are moved forward said runners also carrying a tilting foot plate pivoted thereto near its 80 forward end said foot plate carrying means to secure the same to the foot.

3. The combination in a skee or skate of 85 two parallel runners carrying dogs between them tending to stop any backward motion of said runners, a spring foot plate pivoted near its forward end to said runners having lips extending upward on its forward corners and carrying a toe strap near its forward end and carrying an instep strap at 90 its rear end and carrying a heel strap extending to the rear on either side from near the forward end of said spring foot plate.

GEORGE LANDER JACQUES.
